UNITED STATES PATENT OFFICE.

GEORGE B. GROVER, OF LYNN, MASSACHUSETTS.

BUFFING-MACHINE.

1,024,628.

Specification of Letters Patent. Patented Apr. 30, 1912.

Application filed March 23, 1911. Serial No. 616,426.

To all whom it may concern:

Be it known that I, GEORGE B. GROVER, of Lynn, in the county of Essex and State of Massachusetts, have invented certain new 5 and useful Improvements in Buffing-Machines, of which the following is a specification.

The present invention relates to a machine for buffing leather, particularly such 10 articles as counters and box toes which are used for stiffening the rear parts and toes respectively of boots and shoes.

The machine is capable of being used for buffing articles of other sorts, but it has its 15 particular use in connection with articles of the particular character indicated.

My object has been to produce a machine by which the inner surfaces of the blanks from which the counters and box toes are 20 made may be buffed or sandpapered over their entire surface, even to the thin skived edges thereof. It should be borne in mind that such blanks are first skived on the flesh side around their outlines so as to reduce 25 the blanks to thin edges at their perimeters. As a result of the skiving the intersections of the bevels with each other at the corners of the blanks and with the flesh surface of the leather elsewhere, are rough and marred 30 by irregular ridges and tufts of the uncut leather fibers. These uneven and irregular places are ground off and made smooth by passing the blanks in contact with a buffing roll having its surface made of sandpaper 35 or equivalent abrasive material.

My invention has for its object to provide an automatic machine in which the blanks may be so held that not only are the rough parts of the skived surface made 40 smooth, but also the bevels are smoothed entirely to the edges of the blanks, and the skived edges may, if desired, be reduced to knife edges without removing too much of the stock in the central and thick part 45 of the blank.

My principal object is to combine the capability of doing this work with rapidity of operation, and to provide the machine with means by which the article may be 50 securely held while being buffed, while reducing the number of necessary parts to the minimum and making these parts of simple construction.

Another object is to enable the machine 55 to be used indifferently for buffing or scour-

ing uneven surfaces such as already noted, and for scouring surfaces of articles of substantially uniform thickness.

In carrying the foregoing objects into effect I have devised a machine embodying 60 novel features which will be hereinafter fully described and claimed.

Referring to the drawings, Figure 1 represents a front elevation of such a machine. Fig. 2 represents a plan of the machine. 65 Fig. 3 is a cross section on line 3—3 of Fig. 2. Fig. 4 is a vertical section on line 4—4 of Fig. 1. Fig. 5 is a front elevation on an enlarged scale of the working parts at the right-hand end of the machine. Fig. 6 is 70 a plan view of the same. Fig. 7 is a rear elevation of the same. Fig. 8 is a longitudinal section on an enlarged scale on line 8—8 of Fig. 2. Fig. 9 is a cross section on line 9—9 of Fig. 2, also on an enlarged 75 scale. Fig. 10 is a cross-section on line 10—10 of Fig. 8. Figs. 11, 12, 13 and 14 are sectional views similar to Fig. 10 showing modifications in the work support 80 adapted for different sorts of work.

The same reference characters indicate the same parts in all the figures.

The machine includes in its construction frames 1 and 2 at front and rear respectively, and a table 3 supported upon the 85 tops of the end frames. The driving mechanism is mounted upon the frames below the table, while the parts which act directly upon the work and which may be called the working parts are arranged above the 90 table. These working parts include a buffing roll 4, a brush 5, a holding roll 6, feed rolls 7 and 8 and a work carrier 9. There is also a blower 10 for carrying away the dust produced by the buffing roll. 95

The buffing roll, brush and blower fan are driven at a high rate of speed, while the work carrier is moved at a low speed. Power from any suitable source is delivered to a main shaft 11 through a belt passing about one of the two pulleys 12, 13. Secured upon the shaft 11 also is a pulley 14 around which passes a belt 15 which drives the buffing roll and blower. This belt passes around both a pulley 16 secured to the shaft 100 17 of the buffing roll and a pulley 18 on the shaft of the blower fan, being caused to hug these pulleys by an intermediate pulley wheel 19 which also serves as a slack adjuster. The brush 5 is driven from the 110

shaft 17 by a belt 20 passing around a pulley 21 on said shaft and another pulley 22 on the shaft of the brush. As the shaft 11 is driven at a high speed, those rotating elements which are thus driven directly therefrom are also caused to rotate at a high speed.

For moving the work carriage and feed rolls at a slow speed I provide a speed-reducing train consisting of a step pulley 23 on a countershaft 24, which is driven by a belt 25 from a step pulley 26 on the shaft 11, a pinion 27 connected with pulley 23, a gear 28 on a third shaft 29, and a pinion 30 on shaft 29 meshing with a gear 31. The pulley 23 and gear 31 are both supported on shaft 24, but may rotate loosely thereon. The gear, however, may be connected with the shaft by means of a clutch member 33 secured to the shaft, having a set of clutch teeth 34 with which complementary teeth 35 on the gear are adapted to engage. Such engagement is effected through a treadle 36 on a lever 37 which is pivoted to a pin 38 held in lugs 39 on a part of the frame 1. Lever 37 is pivoted to a link 40, which is also pivoted to a lever 41 hung at 42 upon a bracket 43 projecting from one of the bearings 44 of shaft 24. Said lever 41 has a yoke 45 embracing the hub of gear 31 and provided with studs entering a groove 46 in such hub. Upon depressing the treadle the gear is so moved as to engage its teeth 35 with the teeth of clutch 33. When this engagement is made the shaft 24 is turned at a slow speed through the speed-reducing mechanism just described. A spring 47 tends to disconnect the clutch members. As the pulleys 23 and 26 have several steps, several different speeds may be imparted to the shaft 24, all of which are much lower than the speed of shaft 11.

The shaft 24 is secured to a disk 48 having a cam path 49 (Fig. 1) in which is contained a roll 50 carried by a lever 51 pivoted at 52 upon a bracket 53 secured to a part of the frame. The lever 51 moves the work carriage 9 through a link 54 connected to an arm 55 of the carriage and to the lever, or rocker 51. Provision is made for attaching the link 54 to different points of the rocker 51 so as to vary the length of travel of the work carriage according to the size of the work pieces. Accordingly the rocker is provided with a number of pins 56 over any one of which the hooked end of the link may pass. When the link is thus hooked over any of the pins, it is secured by a thimble 57 which fits over the pin and into the hook. The opening in the under side of the hook is smaller than the diameter of the thimble but greater than the diameter of the stud, so that the link cannot be displaced when the thimble is in place, but can be readily

removed from one stud and slipped over another when the thimble is removed. As shown in the drawings, the arm or rocker 51 is designed for six different sizes of work, and it is so shaped that when at the extreme right hand end of its travel the carriage will be at the same point when connected with any one of the pins. That is, the arm is so shaped that when both it and the carriage are at their extreme right hand travel the link may be connected with any of the studs without requiring either the link or arm to be shifted. On the other limit of travel, however, the position of the carriage varies greatly according to which stud the link is engaged with, as will be readily evident from an inspection of Fig. 1 which shows the parts at this limit of their travel. The carriage 9 is formed as a slide having lips 58 which travel between guides 59 on a part of the table and are retained by strips 60 which overhang the lips. The central part of the carriage is recessed, leaving an open space 61, and over the top of the recess is mounted a removable plate 62 which has beveled edges adapted to slide in undercut grooves 63 in the opposite sides of the carriage, as is shown best in Fig. 10. Part of the plate 62 is cut out at 64 to provide an open space having beveled edges 65. The beveled edges of the open space correspond in shape to the skived edges of the blanks on which the machine operates. In the case of a counter the shape of these bevels is the same as the shape of the counter, while for a box toe the shape is that of the box toe. The beveled portion 65 forms a depression of which the outline and size correspond exactly to a counter or box toe of a particular style and size, and the open space is of the same size and shape as the raised portion left after the counter or other blank has been skived. Thus when the blank is placed on the plate directly over the opening its skived edges rest on the beveled portion 65 and its thick central part may be depressed into the opening 64. The work carrier travels under the buffing roll practically in contact therewith so that the surface of the work is brought into actual contact with the surface of the roll. The thick central part of the work is able to yield into the opening 64 when pressed upon by the roll. Thus the skived face of the blank is brought substantially level and is buffed over its entire surface, the skived edges being smoothed and cut away quite to the perimeter of the blank, without causing the thickness of the central part, where thickness is required, to be materially reduced. Plates apertured for blanks of different characters, sizes and styles may readily be substituted for one another by being slipped endwise into and out of the grooves of the carriage.

When in place they are secured by clamping means such as a bolt 66 which draws one side member of the carriage toward the other and thus binds the edges of the plate. 5 Preferably the carriage is made in one piece having side members and a connecting transverse web. A slot is cut between one of the side members and the web for a part of the length of the carriage, whereby one 10 of the side members is permitted to spring enough to grip and release the plate. The clamping bolt is passed through the side member and threaded into the web as shown in Fig. 10, its head being contained in a recess 67 in the side member, whereby it is 15 protected from injury but is accessible to a socket wrench.

The movement of the carriage in feeding the work to the buffing roll is from left to 20 right with reference to Figs. 1 and 8, and in order that the work may be held upon the supporting plate, a clamping foot 68 is provided. This foot is mounted upon a holder 69 which has a pivot pin 70 projecting 25 at both ends and contained between guide fingers 71 which are carried by the work carriage or slide. These fingers are formed upon a plate 72 which is secured to the under side of the web of the carriage, and project 30 to the left therefrom. They are arranged in pairs flanking the holder 69, and each pair confining and guiding one of the ends of the pivot pin 70. A part of the holder extends downwardly toward the bed or table 35 of the machine and has rolls 73 and 74 which engage cam bars or plates 75, 76 which are fixed to the bed. A spring 77 is connected at its opposite ends with studs or hooks 78, 79 projecting respectively from the plate 72 40 and holder 69. Such spring keeps the holder 69 at the inner end of the fingers 71 and tends to tilt the holder so as to raise the clamping foot 68. When the carriage is at the outer limit of its movement and the 45 roll 73 is over the low part of the cam 75, the spring is effective to raise the foot, as shown in Fig. 8, so that a blank may be slipped under it. As the carriage moves toward the buffing roll, the foot-holder is 50 tilted by the cam 75 and causes the foot to press on the work and secure it against displacement by the buffing roll. Pressure is applied from the holder to the foot yieldingly in order that the foot may accommodate 55 date blanks of various thicknesses, and to this end the foot is pivoted to the holder upon a pivot pin 80 and is acted upon by a spring 81. The latter surrounds a post 82 projecting from the holder and bears against 60 an abutment 83 of the holder and a collar 84 which slides upon the post and is contained between the arms of a fork 85 on the clamping foot, such arms having studs 86 contained in a groove 87 of the collar. A

nut 88 is used to adjust the tension of the 65 spring.

The cam 76 extends beyond the cam 75 and near its right hand end is provided with a depression 76^a, adjacent to which is a stop 89. The cams 75 and 76 are made separate 70 in order that cam 75 may be removed and a longer or shorter cam substituted when blanks of greater or less length are to be acted upon. It is intended that the clamping foot should operate immediately after 75 the carriage commences its travel, and it is therefore necessary that a cam 75 of such length should be used as to secure this result and allow the clamping foot to rise when the carriage is at the left hand limit. 80 Accordingly when the connection of the link 54 with the arm 51 is shifted as above described to increase or diminish the length of travel of the carriage, it is necessary to change the cam 75 correspondingly. The 85 cam 76 alone serves to operate the foot with blanks of the shortest length, and so at its left hand end has a depression 76^b which is located at the point where the roll 74 lies when the link 54 is connected to the lower- 90 most stud upon the arm 51 and is at the left hand limit of motion. The rolls 73 and 74 are mounted side by side upon the same stud so that they engage the cams 75 and 76 respectively. As the carriage always stops at 95 the same point in its feeding travel, whatever may be the length of such travel, the position of the cam depression 76^a need not be changed.

Beside the carriage is mounted a gage-holder 90 which supports gages 91 and 92. One of these gages 91 is formed to engage one of the corners of the blanks, while the other gage 92 is engaged by the edge of the blank. These two gages position the blank 100 accurately and are adjustable so that any part of the blank may come over the opening 64, having longitudinal slots through which pass pins or bolts 93, about which they may move angularly and longitudinally. Clamping collars 94 are mounted upon the bolts and secure the gages. The gage-holder 90 is movable with the carriage for a short distance in order to hold the work in place until the latter is grasped by the clamping foot, and to this end is arranged to slide upon a guide 95 having an undercut guideway, as shown in Fig. 9. One side of the guideway is formed by an adjustable gib 96. The guide has an abutment collar 98 through which passes a pin 99 connected to the gage-holder and having a head 100 on its outer end. A spring 101 bears against the abutment collar and against the holder tending to move the latter in the same direction as that in which the carriage moves when feeding. A shoulder 102 on the gage-holder bears against a

shoulder 103 on the carriage and is held against such shoulder by the spring. When the carriage commences its feeding movement the gage-holder is caused to follow it by the spring until it is arrested by the head 100 coming in contact with the collar 98. By this time the clamping foot has acted and the gages the not needed. In order that the gage-holder may be placed at the different points to which the carriage returns, the guide 95 is also movable, being supported upon a shelf 104 secured to the side of the carriage guideway and being provided with a post 105 passing through a longitudinal slot 106 in such shelf. A spring 107 presses a friction pad or plate 108 against the under side of the shelf. Such pad or plate may be of any material having sufficient friction, and is preferably wood. Adjustable nuts 109 on the post regulate the degree of friction. Thus whenever the travel of the carriage is changed as previously described, the gage-holder may be readily shifted to correspond with the changed outer limit of travel.

The holding roll 6 previously mentioned is located just beyond the buffing roll and immediately above the plane of the supporting plate 62, so as to engage the work after it passes the buffing roll and prevent it from being displaced by the buffing roll, particularly after it has been released by the clamping foot. This holding roll is driven with a peripheral speed equal to the travel of the table, and is preferably driven by the table itself. It is mounted upon a shaft which is held in arms 110, 111 and is provided with a friction roll 112 which bears against the upper surface of the carriage. The arms 110 and 111 are pivoted upon brackets at opposite sides of the carriage and are acted upon by springs 113, 114, which draw the rolls toward the table. Adjustable stops 115, 116 limit the pressure with which the roll 6 and roll 112 engage the work and the carriage respectively. After passing the holding roll the work rides up on a lifter 117 which is preferably a wedge-shaped block having a sharp edge lying as close as possible to the plane of the carriage and plate 62. The lifter is secured to the bracket 118 by a bolt 119 which passes through a slot 120 in the bracket (Fig. 7) and enables the lifter to be adjusted until its edge may enter between the surface of the plate 16 and the advancing end of the work.

While passing over the lifter the work is cleaned by the brush 5 previously described, which is rotated by the shaft 17 of the buffing roll at a high speed, as previously described. The work is finally wholly withdrawn from the machine by the feed rolls 7 and 8 previously mentioned, one of which is above the lifter and the other of which is

contained in a recess 124 in the lifter. The roll 7 is driven from the shaft 29 by means of a pulley 125 thereon, a belt 126 surrounding said pulley, a shaft 127 which carries a pulley 128 also engaged by the belt, and gears 129 and 130 on the shaft 127 and the shaft of the roll 7 respectively. The roll is so mounted that it may yield to accommodate work of various thicknesses, being mounted in a holder 131 pivoted upon the shaft 127, which thus permits the roll to rise and descend without taking the gears 130 and 129 out of mesh. The spring 132 presses the roll toward the work, acting against a lug 133 on the holder 131, and reacting against a crossbar 134 extending between the brackets 118 and 135. The spring is held in place and its tension regulated by a bolt 136 passing through the lug 133 and crossbar 134, and having an adjusting nut 137 threaded upon one end. Beyond the lifter block is a plate 138 upon which the work is fed by the rolls 7 and 8. This plate is inclined downwardly toward the front of the machine at such a pitch that the scoured articles deposited upon it fall readily into the receptacle placed beneath.

I have made provision for adjusting the buffing roll so that it may remove more or less stock from the work, and also so that it may be inclined and act to a greater extent at one edge than at the other of the work. For this purpose the bearings 139 and 140 in which the shaft 17 is held are carried by vertically movable posts 141, 142, respectively, shown in Figs. 2, 3, and 4. These posts slide in upright guides 143 and 144 and are entered by adjusting screws 145 and 146 respectively. The adjusting screws carry bevel pinions 147, 148, which are engaged by pinions 149, 150 on a shaft 151. The shaft is mounted in bearings 152 which hang from the under side of the table, and has no connection with the other parts of the machine. It carries a hand wheel 153 at the rear by which it may be turned to raise or lower the shaft 17 through the gears and screws described. One of the pinions, as 149, may be made either fast or loose upon the shaft, while the other pinion 150 is permanently fast. Thus by loosening the pinion 149, one end only of the buffing roll shaft may be raised or lowered, whereby to alter the inclination of the axis of the roll when it is desired to grind off the work more at one side of its longitudinal center than at the other. To permit of thus changing the line of the shaft without causing it to bind in its bearings, the latter are pivotally connected to posts 141 and 142, as shown in Fig. 3. Each post has arms 154 embracing the bearing in which are held studs 155 entering sockets in opposite sides of the bearing. The studs are adjustable

and their inner ends are preferably tapered so as to take up looseness. Thus one end of the roll shaft may be raised or lowered more than the other, without causing the bearings 5 to bind.

Provision is made for adjusting the tension of the belt 15 which drives the buffing roll and the blower fan. For this purpose the take-up roll 19 is carried by an arm 156 10 pivoted at one end at 157 and having a handle 158 at the other end by which it may be raised or lowered. A clamping bolt 159 passes through a slot 160 in the arm 156, and into a shoulder 161 upon the table, permitting the arm to be raised or lowered and 15 to be clamped in any position.

The blower hereinbefore referred to is not a material part of my invention, but is provided merely for the ordinary purpose of 20 carrying away dust. With it is designed to be used a hood and conduit, the former being placed over the buffing roll and brush and the latter being connected with the intake of the blower. As these parts obscure 25 the greater part of the buffing roll, brush and feed rolls, they are not shown in the drawings, and as they are not claimed as a part of my invention, the omission is immaterial.

30 I will now describe the operation of the machine:—The parts being in the positions shown in the drawings, and a supporting plate 62 designed to support a counter being secured upon the carriage, the counter 35 to be buffed is laid upon the plate with its grain side downward and the skived surface upward. The gages being adjusted as shown in Fig. 2 locate the blank so that its edges coincide with the outer boundary of 40 the beveled portion 65, the thick central part of the blank being over the space 64. The operator then presses upon the treadle 36, connecting the clutch members 34, 35 and causing the carriage to be given its 45 feeding movement through the medium of cam 48, rocker 51 and link 54. The gage-holder and gages follow the carriage under the influence of spring 101 until the roll 73 of the foot-holder 68 has ridden up on the 50 cam 75 and caused the foot to grip the end of the blank. Thereupon the gage-holder is arrested and the carriage proceeds under the buffing roll carrying the blank toward the latter. As the blank is unsecured at its 55 end nearest to the roll, which for convenience of description I will term the forward end, the roll is driven so that that portion which acts on the work travels in the same direction as the carriage. As the peripheral 60 speed of the roll is much greater than the speed of the carriage, the abrasive surface of the roll rubs over the work and cuts away all uneven and rough parts. It also exerts a pull on the blank tending to drag

it forward faster than the carriage moves, 65 which pull is resisted by the grip of the clamping foot. The latter and its holder being supported by the fingers 71, which in turn are carried by the work carriage, and being drawn forward by the spring 77 70 continue in motion until the foot is as close to the surface of the buffing roll as it can safely be brought. At this time, however, the roll 74 drops into the cam depression 76^a and the roll 73 strikes the stop 89. Thus 75 the foot is arrested so that it does not strike and injure the buffing roll, and at the same time it is raised so as to allow the carriage to continue its travel with the blank. The stoppage of the foot and its holder offers no 80 impediment to the continued movement of the carriage because the foot-holder is loosely held between the fingers 71 and otherwise has no connection with the carriage except through the spring 77 which is comparatively light and yields easily. This yielding mode of connecting the foot to the carriage also permits the supporting plates 85 62 to be easily removed and replaced, because prior to thus removing or placing one 90 of these plates the foot-holder is withdrawn from the guides or fingers, leaving sufficient free space over the fingers 71 to enable the plate to be slipped out of or into the guide-ways 63. When the blank is released by 95 the raising of the foot, it has already passed the buffing roll far enough to be engaged by the holding roll 6 and to be retarded by the latter so as under no conditions to travel faster than the carriage. The sizes of the 100 parts are so designed that even the shortest blanks are engaged by the holding roll before they are released by the clamping foot. The blank 6 rides up on the wedge or lifter 117, is cleaned by the brush 5 and then fed 105 by the rolls 7 and 8 out upon the delivery table 138 whence it falls finished into the receptacle.

Mention has been made of the space 61 beneath the plate 62 and between the side 110 members of the carriage 9. In other words the carriage has a central depression or channel of uniform depth between its side members. This space or channel is an important feature of the invention. As it is 115 considerably deeper than the thickness of any article designed to be operated upon by the machine, it allows the central part of the article or blank to sink through the opening 64 in the plate to such an extent 120 as may be required to bring the highest point of its skived side into the plane of the support 62, so that the bevels of the blank may be ground off to as thin edges as desired without causing too much material to 125 be removed from the center of the blank. The plate 62, which is preferably a thin steel plate, is supported adjacent to the out-

lines of the aperture by studs 162 which are set into holes 163 in the transverse web of the carriage. There is a large number of such holes and the studs may be set into any 5 of them and so placed as to give support to the plate near the aperture thereof, whatever may be the size and form of the aperture. These studs have heads of exactly the right height to hold the plate horizontal.

10 For some classes of work such as box toes, where the area of the blank is great as compared with the length of its perimeter, and also when working upon soft and limp stock, I have found it desirable to give 15 a certain amount of support to that part of the blank which is pressed through the aperture 64. For this purpose I remove the studs 162 and place in the chamber 61 a pad of soft and elastic material such as 20 rubber. The pad, of course, does not prevent the blank from being depressed through the opening 64, but gives a yielding support to the central part of the blank in a plane below that of the supporting 25 plate. The plate 62 may also be removed altogether and the pad alone substituted, whereupon the carriage is fitted to feed articles of uniform thickness such as shoe soles and the like to the buffing roll.

30 Fig. 11 shows the use of a rubber pad 170 for the purpose last above indicated, such pad being placed under the plate 62 and furnishing a yielding support for the central part of the box toe or other blank which is 35 placed over the aperture of the plate 62, and the edges of which are rigidly supported by the plate. The rubber pad is one form of a yielding or spring support for the central part of the blank. A modification of this 40 idea including another form of spring support is illustrated in Fig. 12, where the support is a plate 171 extending across the aperture of the plate 62 and being supported by springs 173. When the plate 62 is removed and the rubber pad or other spring support alone holds the articles, the carriage has the appearance shown in Fig. 13 where the rubber pad is again represented by 170 45 and the article to be buffed, such as a shoe sole, by 174. When an article of uniform thickness is to be buffed it may be placed upon any part of the supporting surface provided only that it is so placed as to come 50 against the abrasive surface of the roll, and 55 provided also it may be gripped by the clamping foot. I contemplate, however, that for some classes of work where the rubber pad constitutes the spring support, the friction of the article on the rubber may be 60 sufficient to withhold it against the drawing action of the buffing roll, and in such cases I may omit to secure it by the clamping foot.

A modification of the idea last described

is represented in Fig. 14 where the sole or 65 other article of approximately uniform thickness is placed upon a modified form of yielding or spring support, which here is a plate 175 mounted upon springs 176. The plate itself is rigid, but by virtue of the 70 springs it may yield to various degrees to accommodate articles of different thicknesses, while one side or end of the plate may yield more or less than the opposite side or end when the articles are thicker at 75 one side or end than at the other. The rubber pad is capable of yielding locally at every point, and so may be used where the articles have small areas of uneven thickness.

I desire to note at this point that the 80 buffer may be of any character whatever as desired, and that its specific character is not a feature of the invention. I have chosen for illustration as the buffer a rotating roll, for such is the almost universal form of the 85 buffing tool. I reserve the right, however, to use any other kind of buffer or buffing tool than a roll, if at any time some other sort of tool may be found practical or desirable for any purpose, and I consider that 90 the substitution of any other such tool is within the scope of my invention as expressed in the claims. Where the term "buffing roll" is used in the latter, it is to be understood in a generic sense as meaning 95 any kind of a tool suitable for buffing purposes.

I claim,

1. A buffing machine comprising a buffing roll and a work support, having a recess entirely surrounded by the material of the support, the rim of which is beveled, and means for causing said work-support to travel reciprocatively past the roll in a straight line.

2. A machine for buffing the skived surfaces of articles having skived or beveled edges, comprising a buffing roll, and a work support, the latter consisting of a plate having an opening through it of a form substantially the same and an area less than, the form and area respectively of the article.

3. In a machine of the character and for the purpose described, a work supporting plate having an opening through its entire thickness and beveled at the edge of the opening.

4. In a buffing machine the combination with a buffing roll of a work carriage, a guide connected with the carriage and extending in the direction of movement of the latter, a work clamp held by such guide and movable therein relatively to the carriage, and a yielding means connected with the clamp and carriage tending to place and retain the former in its operative position.

5. A buffing machine comprising in combination a reciprocating work carriage,

means for moving such carriage back and forth, a clamping means associated with the carriage for securing articles to be buffed thereon, a buffing roll mounted in close proximity to the supporting portion of the carriage, a holding roll arranged adjacent to and beyond the buffing roll for holding the advancing ends of the articles as they pass the buffing roll, means for driving said roll with its peripheral speed substantially the same as the speed of the table, a lifter having an edge arranged in close contact with the supporting surface of the carriage, and feed rolls arranged to grasp the blank as it passes over such lifter and remove it therefrom.

6. In a buffing machine the combination of a work carriage having a substantially plane work-supporting surface, a buffing roll mounted with its surface in close proximity to the said supporting surface, a clamp associated with the carriage at one side of the buffing roll, a holding roll located close to the surface of the carriage upon the opposite side of the buffing roll, and means whereby the carriage drives said holding roll at a peripheral speed substantially equal to the feeding travel of the carriage.

7. The combination of a buffing roll, a carriage adapted to support work pieces and to carry said pieces past the roll, a gage for locating work pieces upon the carriage, a holder for said gage movable in the direction of feeding movement of the carriage, means for so moving the gage in unison with the carriage, a clamping foot for gripping the work on the carriage, and means operated by the movement of the carriage for causing said foot to grip the work, the movement of the gage-holder simultaneously with the carriage causing the gage to retain the work in proper position until the clamping foot has become operative.

8. In a buffing machine in combination with a buffing roll, a carriage movable back and forth adapted to support work pieces of various lengths, and carry them past the roll, and means for so moving the carriage comprising a pivoted actuator and a link pivoted to the carriage and arm, together with means for securing the link at points on the actuator varying in distance from the pivot thereof so as to vary the extent of movement of the carriage, such points being in the arc of a circle of which the said link is the radius and of which the center coincides with pivot of the link when both carriage and actuator are at the end of feeding travel, whereby the end of the feed movement of the carriage occurs at the same point under all conditions.

9. In a buffing machine a buffing roll, a work carriage, means for moving said carriage back and forth past the roll, said

means being adjustable for varying the length of travel of the carriage in accordance with the length of the work, a work-holding device associated with the carriage, means operated by the feeding movement of the carriage for causing said holding device to become operative, a gage arranged in such relation to the carriage in the outermost limit of its travel as to locate the work pieces correctly thereon, and means for moving the gage synchronously with the carriage until the work-holding device has become operative, such gage being also adjustable with the means for moving it into various positions to correspond with the various limits of travel of the carriage.

10. In a buffing machine a work-holder comprising a carriage having a recess, and a plate bridging such recess, the plate having an opening of form and area respectively similar to and less than the form and area of a shoe stiffener blank.

11. In a machine of the character described, a work-holder consisting of a carriage having a central depression or recess and a supporting plate detachably secured to the carriage over such recess, and having an opening extending entirely through it of a form similar to the form of a shoe stiffener blank, and dimensions less than corresponding dimensions of such blank.

12. In a buffing machine a work-carrying slide or carriage having a depression or recess in its upper side, adapted to contain an elastic pad, and having guides in its flanking side walls adapted to contain detachably a holding plate.

13. In a machine of the character described, the combination with a buffing roll of a traveling carriage, a clamp for holding the work upon the carriage during its movement toward the buffing roll, a holding roll for retarding the work as it passes the buffing roll, feeding rolls for carrying away the finished work, means for causing the clamp to grip the work, means for driving the holding roll with a peripheral speed substantially equal to that of the carriage, and means for driving the feeding rolls, such clamp, holding roll and feeding roll being yieldingly mounted to accommodate stock of different thicknesses.

14. In a machine of the character described, the combination with a buffing roll of a carriage arranged to reciprocate in a straight line past the operative face of the roll, a yielding support for the article to be buffed of greater superficial area than the article secured upon the carriage, and means for securing the article upon the support to prevent displacement by the friction of the buffing roll.

15. In a buffing machine, a work support constructed to hold skived shoe stiffener

blanks while being buffed, said support having rigid means for supporting only the skived edges of the blanks; and a yielding support for the central part of the blank.

5 16. In a buffing machine, a work support comprising in combination a plate having a recess, said plate being adapted to support the edges of the work at the boundary of the recess, and a spring beneath the re-

cess for yieldingly supporting the central 10 part of the work.

In testimony whereof I have affixed my signature, in presence of two witnesses.

GEORGE B. GROVER.
